UNITED STATES PATENT OFFICE

149,938

DESIGN FOR A BOTTLE

Marguerite Casséus D'Hennery, Paris, France

Application June 19, 1946, Serial No. 130,847

Term of patent 3½ years

(Cl. D58—6)

To all whom it may concern:

Be it known that I, Marguerite Casséus d'Hennery, a citizen of France, residing at Paris, France, have invented a new, original, and ornamental Design for a Bottle, of which the following is a specification, reference being had to the accompanying drawing, forming part thereof.

The figure is a perspective view of a bottle, showing my new design.

The rear portion of the bottle is the same as the front portion shown in the drawing.

I claim:

The ornamental design for a bottle, substantially as shown and described.

MARGUERITE CASSÉUS D'HENNEY.
